UNITED STATES PATENT OFFICE.

CHARLES G. HAYES, OF CHICAGO, ILLINOIS.

DESIGN FOR A REVOLVING STREET SIGNAL.

Application filed May 31, 1923. Serial No. 6,368. Term of patent 7 years.

To all whom it may concern:

Be it known that I, CHARLES G. HAYES, a citizen of the United States, residing at Chicago, in the county of Cook and State of Illinois, have invented a new, original, and ornamental Design for Revolving Street Signals, of which the following is a specification, reference being had to the accompanying drawing, forming a part thereof.

Figure 1 is a side view in elevation of a revolving street signal showing my new design.

Figure 2 is a front view in elevation of the design shown in Figure 1.

I claim:

The ornamental design for a revolving street signal, as shown.

Signed at Chicago, in the county of Cook, and State of Illinois, this 29th day of May, 1923.

CHARLES G. HAYES.
